INSEAM JOINT FORMING MACHINE

Lester S. Macdonald, Beverly, Mass., assignor to
United Shoe Machinery Corporation, Flemington, N. J., a corporation of New Jersey

Application August 30, 1941, Serial No. 408,935

41 Claims.

(Cl. 12—51)

This invention relates to machines for shaping uppers or upper parts over forms and is herein illustrated in its application to machines for use in the manufacture of Goodyear welt shoes to shape the inseam substance, that is, the lasting margin of the upper together with the flange of a molded counter and the insole rib, at those portions where the forward portions of the counter wings lie adjacent to the end portions of the insole rib, said portions being commonly referred to as the inseam joint.

In the manufacture of Goodyear welt shoes provided with molded counters, it is desirable that the upper materials, particularly the counter, be prepared for the side lasting operation by forming said materials at the inseam joint to fit into the angle defined by the feather and the rib of the insole. Such preforming of the upper materials enables the side lasting machine to drive fastenings through those portions of the upper materials and the rib of the insole at the desired location with the least inconvenience to the side lasting machine operator. It is not practicable to undertake to shape these portions of the counter in the side lasting machine itself since in the operation of that machine the shoe is supported by the operator and consequently, there is no opportunity for applying to the shoe sufficient force to perform the counter-shaping operation. But when the upper and the counter are shaped prior to the side lasting operation, the wiping mechanism of the side lasting machine will easily bring the upper materials into lasted position and the fastenings will be inserted at the apex of the angle formed in the forward extremity of the counter and the upper, and thus said parts will be secured tightly and compactly to the insole rib. The side lasting of this portion of the upper is a critical operation in the manufacture of the shoe since an upper lasted in tightly and securely fastened at the ends of the insole rib presents little difficulty in the subsequent bottoming operation whereas if the side lasting operator fails to last said portions of the upper in tightly against the insole rib and thus causes the lasting fastenings to extend too far out toward the sides of the shoe, both the inseam stitches and the outsole attaching stitches at the inseam joint will extend too far out unless extreme care is taken in the stitching operations. If the outsole-attaching stitches extend too far out, there is always the danger that the edge trimmer will cut into them and cripple the shoe.

It is an object of the present invention to provide a machine for preparing the uppers and

counters of Goodyear welt shoes for the side lasting operation by preforming the upper parts at the inseam joint to fit into the angle defined by the rib and the feather of the insole.

It is a further object of the present invention to provide an improved machine of this type capable of simultaneously forming the inseam substance at opposite sides of the shoe.

With the above object in view, the present invention in one aspect thereof comprises a machine for forming shoe bottom substance into upstanding flanges at opposite sides of a shoe bottom comprising oppositely disposed abutment members or wipers constructed and arranged to operate concomitantly on the outer portions of the inseam substance, means constructed and arranged to engage opposite sides of the shoe to determine the operative position of each abutment member widthwise of the shoe, and oppositely disposed flange formers constructed and arranged to move widthwise of the shoe away from each other to form the shoe bottom substance against the wipers. In order to insure the correct placement of the end portions of the inseam, the flange formers operate on the inseam substance at predetermined points equally distant from the edge of the last bottom.

For operating the wipers, the illustrated machine is provided with novel mechanism whereby the wipers are advanced simultaneously until one of them is arrested by engagement with the shoe, and thereafter the other wiper is advanced independently until it, too, is arrested by engagement with the shoe. This novel operating mechanism includes a worm shaft carrying two worms threaded in opposite directions and meshing with worm gears having operating connections to the wipers, said worm shaft being arranged to move endwise after one of the wipers has been arrested by engagement with the shoe, thus enabling the worm which operates said wiper to continue to turn while the worm gear with which it meshes remains stationary. In accordance with a further feature of the invention, the wipers are movable in rectilinear paths extending widthwise of the shoe to overwipe a narrow area of the heel seat portion of the upper and are arranged for swinging movement to overwipe portions of the lasting margin extending toewards from said area. In operating on Goodyear welt shoes, said narrow area is the forward portion of the heel seat immediately adjacent to the end of the insole rib. The novel wiper herein illustrated is provided with an extension or finger for wiping said narrow area over the

margin of the insole and beyond the line of the insole rib in order to flatten the entire width of the lasting margin at that portion of the upper against the insole to facilitate the subsequent heel end lasting operation. In the illustrated machine, the novel flange forming mechanism includes a flange former which advances from a remote position widthwise of the shoe inwardly over the insole rib at an elevation well above the shoe, then heightwise of the shoe into engagement with the insole and finally outwardly into flange-forming engagement with the insole rib. In accordance with a further feature of the invention, the abutment member and the flange former are so constructed and arranged that their work-engaging surfaces extend upwardly with an outward inclination so as to overmold the upper materials, particularly the counter flange, to an extent commensurate with the normal spring back of the upturned portion of said flange. Another feature of the invention resides in the provision of actuating means constructed and arranged to apply equal flange-forming pressure to the abutment members and flange formers, thus obviating the need of means for locking the abutment members to receive the force of the flange formers.

In accordance with a further feature of the invention, the wipers and flange formers are mounted on carriers which, in turn, are mounted on slides which move inwardly to impart an initial overwiping movement to the wipers after which the carriers move relatively to the slides to complete the operation of the wipers. In the illustrated machine, the carriers move relatively to the slides in arcuate paths to impart swinging movement to the wipers about axes coincident with the ends of the insole rib.

To assist in the formation of a well defined angle in the flange of the counter and the everlasting margin of the upper, the illustrated wipers, in accordance with a further feature of the invention, are provided with beads extending downwardly from their wiping edges and means is provided for effecting relative movement of the wipers and the shoe heightwise of the shoe to cause said beads to indent the work. As herein illustrated, the wipers are held against heightwise movement while a work support is moved upwardly by power to force the shoe against the beaded portions of the wipers. For imparting upward movement to the work support, the illustrated machine is provided with novel means comprising an actuator, a body of fluid against which the actuator operates, a fluid chamber formed in the relatively moving parts, and a valve outside said chamber constructed and arranged to open thereby to release said fluid when the desired upward pressure of the shoe against the wipers is attained. After the valve opens the actuator completes its movement without imparting further upward movement to the work support.

While the invention is herein illustrated in its application to machines for forming the inseam joints of Goodyear welt shoes, it is to be understood that the invention is not thus limited in its scope but in certain aspects it is applicable to machines for shaping other portions of shoe uppers and to machines for operating on shoes other than those of the Goodyear welt type. Thus, the invention in one important aspect consists in the provision in a machine for shaping uppers over lasts of a pair of wipers operable to wipe the lasting margin of an upper over an

insole on a last bottom by an initial movement bodily widthwise only of the last and by a subsequent swinging movement about an axis extending generally heightwise of the upper after the initial movement is completed.

In another aspect, the invention resides in the provision in a shoe machine of a member for operating on a shoe bottom, a carrier on which said member is mounted for relative movements both heightwise and widthwise of the shoe, means for moving the carrier toward the shoe and means for moving said member heightwise into engagement with the shoe bottom then widthwise of the shoe. Said member, as herein illustrated, is the flange former which acts against the inner surface of the insole rib. It will be understood, however, that a member other than a flange former could be incorporated in this combination without departing from the invention.

These and other features of the invention will now be described with reference to the accompanying drawings and pointed out in the appended claims.

In the drawings,

Fig. 1 is a left side elevation of a machine embodying the features of the present invention, parts of the machine being broken away and other parts shown in section;

Figs. 18, 19, and 20 are front elevations illustrating the wipers and flange formers and parts of their operating mechanism at successive stages in the operation of the machine; and

Fig. 21 is an enlarged view illustrating the wiper and flange former at the left side of the machine in their position illustrated in Fig. 20.

The illustrated machine is designed for use in

the manufacture of Goodyear welt shoes. This type of shoe is provided with an insole having a rib to which the lasting margin of the upper together with the flange of the counter are secured.

The illustrated machine is provided with a work support which is moved rearwardly by the operator to locate the shoe lengthwise against a backstop and is moved upwardly by the operation of a treadle to locate the shoe heightwise against a holdown. The operating instrumentalities include a pair of operating members or wipers which first overwipe narrow areas of the heel seat portion of the upper adjacent to the opposite ends of the insole rib, then swing inwardly about axes coincident with the ends of said rib to wipe the upper at the inseam joint inwardly into the angle formed by the rib and the feather of the insole. The upper is provided with a molded counter the forward portions of which are shaped by the operation of the illustrated machine to fit into the angle formed by the rib and the feather of the insole. In thus shaping the forward extremities of the counter, the inner portions of the forward extremities of its sole-attaching margin are flanged upwardly by the operation of flange formers which operate against the inner surface of the insole rib while the wipers remain in their overwiped positions and serve as abutment members against which said flange formers shape the inseam substance, particularly the flange of the counter. During the operation of the flange formers, the work support moves upwardly slightly to cause downwardly extending beaded portions at the wiping edges of said wipers to be impressed into the work and to provide a fulcrum against which the flange formers operate to upturn the inseam substance and mold the counter flange. A pair of slides at opposite sides of the shoe carry the wipers and the flange formers. The operation of the treadle above referred to moves the slides inwardly to operate the wipers, as above described, and to bring the flange formers into position over the insole. The flange formers swing inwardly in unison with the wipers, thus bringing their work-engaging portions into longitudinal alignment with the ends of the insole rib as the overwiping movement of the wipers is arrested by their engagement with the shoe. The resistance of the work to further advancement of the wipers causes the fulcrum of the treadle to shift, whereupon further depression of the treadle operates a one-revolution clutch mechanism to initiate the power cycle of the machine. During the power cycle, the wipers are pressed hard against the shoe, and the flange formers are moved downwardly into engagement with the insole, then outwardly to form the inseam substance against the wipers. Upon completion of these operations, the jack moves downwardly, and the wipers and flange formers are withdrawn to their rest positions.

Referring to Fig. 1, the illustrated machine comprises a standard 20 having a forwardly offset lower portion in which there is mounted a vertically movable table 22, on which there is slidably mounted for rectilinear movement toward and from the front of the machine a work support or jack comprising a heel post 24 and a toe support 26. The operating instrumentalities of the machine are first advanced manually by the depression of a treadle 28 until said instrumentalities meet the resistance of the work, whereupon further depression of said treadle operates a one-revolution clutch mechanism to

initiate the power cycle of the machine. During the first stage of its operation, the treadle 28 swings about a fulcrum 30 at its rear and imparts downward movement to a link 32 and an arm 34 to impart counterclockwise movement to a double acting lever 36. The forward end of said lever acts, through a spring 38 at the lower end of a link 40, to impart upward movement to the table 22 to position a shoe on the jack heightwise thereof against a holdown 42 (Fig. 7) which positions the shoe heightwise relatively to the operating instrumentalities. The holdown is mounted to move upwardly slightly with the shoe during the power cycle of the machine. As herein illustrated, the holdown has an upwardly extending stem 44 surrounded by a spring 45 which resists upward movement of the holdown, said stem extending through an upward extension 46 of the machine standard and carrying at its upper end a locating nut 48. The cylindrical portion 50 of the holdown slides in a counter-bore 52 while the square lower portion 54 engages walls 56 to prevent swiveling movement of the holdown. The link 40 (Fig. 1) acts in a vertical slot 48 in the lower portion of the table 22, which slot accommodates the upward movement of the table during the power cycle of the machine.

The rear end of the lever 36 is connected, by means including a link 48, to mechanism for advancing the operating instrumentalities into work-engaging position. When the resistance of the work to continued advancement of the operating instrumentalities becomes greater than the pressure of a spring 58 against which the treadle acts, the fulcrum of the treadle shifts forwardly to the pivotal connection 60 of the link 32 to the treadle and upward movement is imparted to a slide 62 on which the rear end of the treadle is fulcrumed, this slide being mounted on a fixed vertical shaft 64. During the first stage of depression of the treadle 28, the link 40 imparts clockwise movement to a bell-crank lever 66. This bell-crank lever is loosely mounted on a shaft 68 and has pivoted to its upwardly extending arm a pawl 62 constructed and arranged to act on a ratchet 64 fixed to said shaft. When the machine is at rest, the pawl 62 is held out of engagement with the ratchet, by the engagement of a roll 66 (Fig. 5) on the tail portion of said pawl with a raised portion 68 on the inner surface of a fixed arcuate plate 70, thus permitting adjustive rotation of the shaft 68 in either direction by mechanism hereinafter described. During the clockwise movement of the bell-crank lever 66, a spring 72, connecting the tail portion of the pawl and the upper extremity of the upright arm of the bell-crank lever, swings the pawl into engagement with the ratchet. As the bell-crank lever continues its clockwise movement, the ratchet 64 and its shaft 68 are turned in a clockwise direction, thereby advancing the operating instrumentalities of the machine through mechanism hereinafter described. When the resistance of the work terminates the manual advancement of the operating instrumentalities, the power cycle of the machine is initiated by the operation of a one-revolution clutch mechanism which connects a continuously driven pulley 74 (Fig. 1) with a shaft 76. This shaft carries an eccentric 78, which operates a pitman 80 to impart downward movement to a slide 82. This slide has an upward extension 84, from which a stud 86 (Figs. 3 and 4) extends rearwardly into

a groove 88 in a lever 90, said stud having loosely mounted thereon a block 92 which lies in said groove. The lever 90 is secured to a short shaft 94 journaled in the standard 20 and its rearwardly offset arm 96 is pivoted to the lower end of a link 98 (Figs. 1 and 3), the upper end of which is pivoted to the lower member 100 (Fig. 2) of a pair of normally-closed hinged arms, the upper arm 102 of which is pivoted to a link 104, the upper extremity of which is pivoted to a lever 106 freely mounted on the shaft 60 and carrying at its rear end a pawl 108 constructed and arranged to act on the ratchet 64. The pawl 108 is held out of engagement with the ratchet when the machine is at rest by a raised surface 110 of the plate 70, said raised surface acting against a roll carried by the tail portion of the pawl. A spring 112 (Fig. 5) urges the pawl into ratchet-engaging position. During the greater part of the power cycle of the machine, the links 98 and 104, together with the arms 100 and 102, move downwardly as a unit, turning the ratchet 64 and its shaft 60 in a clockwise direction to complete the actuation of the operating instrumentalities of the machine. After the said instrumentalities have completed their work, further downward movement of the link 98 swings the arm 100 downwardly about its pivotal connection with the arm 102 compressing a spring 114, but imparts no further downward movement to the link 104. It will be understood that the spring 114 normally holds the arms 100 and 102 in their closed position, illustrated in Fig. 2, by its action on a stem 116 carried by the arm 102.

Fast on the shaft 60 to which the ratchet 64 is secured, is a gear sector 118 (Figs. 8 and 9) which meshes with a pinion 120 (Fig. 9) secured to a shaft 122 journaled in the standard 20. At opposite ends of the shaft 122 there are secured two worms 124 threaded in opposite directions and constructed and arranged to mesh with worm gear segments 152 (Fig. 11). In order that the operating instrumentalities at opposite sides of the shoe may advance until each has been arrested by engagement with the shoe, the shaft 122 is so constructed and arranged that after the operating instrumentalities at one side of the machine are arrested by engagement with the shoe, said shaft is moved endwise by reason of the operative movement of the worm 124 at that side of the machine with relation to the stationary worm gear. During such endwise movement, the shaft and the operating instrumentalities at the opposite side of the machine are advanced independently until they, too, are arrested by engagement with the shoe. The teeth of the pinion 120 and the gear segment 118 are of sufficient length to remain in meshing engagement throughout the entire range of endwise movement of the shaft 122. The rotation of the worms 124 advances the operating instrumentalities of the machine widthwise of the shoe toward each other through mechanism to be described. For adjusting the initial positions of the operating instrumentalities for shoes of different widths, a shaft 130 (Figs. 8 and 9) extending from front to back of the machine is provided at its rear end with a worm 132 which meshes with a worm gear 134 loosely mounted on the shaft 60. The worm gear 134 has a concentric counterbore 136 within which is freely mounted the flanged portion 138 (Fig. 10) of a collar 140 secured to the shaft 60. A section of the flange 138 is cut out and a pin 142 in the worm gear 134 extends from the base of the counterbore 136 into the opening thus pro-

vided. When the machine is at rest, the collar and the worm gear are held in their relative position illustrated in Fig. 10 by a torsion spring 144 (Fig. 9) surrounding an extension of the shaft 60 and anchored at one end to the outwardly extending portion of the pin 142 and at the opposite end to a collar 146 secured to said extension. In the operation of the machine, the shaft 60 turns in a direction to move the end wall 148 (Fig. 10) of the flange 138 away from the pin 142 and wind up the torsion spring 144. During the reverse movement of the shaft 60, the collar 140 is returned to its initial position illustrated in Fig. 10. It will be understood that the spring 144 yieldingly holds the worm gear 134 against rotation on the shaft 60 to permit said shaft to turn the worm shaft 122, thereby affording adjustment of the operating instrumentalities of the machine either inwardly toward the shoe or outwardly away from the shoe by turning a handle 150 at the forward end of the shaft 130. The gear segments 152 (Figs. 11 and 13) with which the worms 124 mesh are secured to the rear end portions of shafts 154 extending from front to back of the machine. At their forward ends each of these shafts has fixed thereto an upwardly extending arm 156 which imparts inward and outward movement to a slide 158 which carries operating instrumentalities of the machine. These instrumentalities comprise wipers 160 and flange formers 162. As shown in Fig. 13, the wipers 160 have at their rearward extremities inward extensions or fingers 164. Said fingers over-wipe narrow areas of the heel seat portion of the upper adjacent to the ends of the insole rib. As shown in Fig. 11, the wipers have downwardly and outwardly inclined abutment faces 166 which engage the last to arrest the overwiping movement of the wipers. The flange formers 162 are initially positioned above the level of the shoe bottom and move inwardly simultaneously with the wipers 160 until they are positioned between the insole rib and the longitudinal median line of the shoe, as shown in Fig. 13. The wipers and flange formers at each side of the shoe are mounted on a block 168 which is mounted for arcuate movement in a horizontal plane on an arcuate T-shaped rail 170 which forms the inner extremity of the slide 158. The axis on which the block swings is located at the juncture of the finger 164 with the forwardly extending portion of the wiping edge of the wiper. In the operation of the machine, the slides 158 move inwardly until the rearward extremities of their abutment faces 166 engage the shoe to arrest such inward movement whereupon the blocks 168 swing inwardly to complete the operation of the wipers. Both the inward movement of the slides 158 and the arcuate movement of the blocks 168 are effected by the inward movement of the arms 156 produced by the operation of the worms 124. To this end, each slide 158 carries a sliding pin 172 (Fig. 11) which is mounted in a hollow bracket 174 secured to the slide 158 and connected to the arm 156 by a link 176 pivoted on a short shaft 178 (Figs. 11 and 13) mounted in a head 180 on the pin 172. The shaft 178 is secured to a plate 188 (Fig. 12a) which is attached to a slide 189 mounted in a guideway 191 (Fig. 12) in the slide 158. The rear portion of the shaft 178 carries a pinion 182 and the rear portion of the slide 189 is bored at 193 (Fig. 12a) to receive said pinion, the teeth of the pinion extending above and below said slide for meshing engagement with rack

teeth formed in a plate 184 (Fig. 12) fixed to the slide 158 and with rack teeth in a slide 186 mounted in a guideway in the lower portion of the slide 158 (Fig. 6). In the front face of the slide 186 are rack teeth 190 (Fig. 12) which mesh with a pinion 192 fixed to a short, vertical shaft 194 journaled in the slide 158. Fixed to the upper portion of the shaft 194 is a short arm 196 (Fig. 13) the front end of which has a slot 198 which engages a pin 200 extending upwardly from the block 160. During the initial movement of the arm 196, the sliding pin 172 is held against movement relatively to the slide 158 by a spring 202 surrounding the pin 172 and contained within a counterbore in the bracket 174, said spring acting against a washer 204 on the pin 172 to hold the head 180 in contact with the bracket 174. When the movement of the slide 158 is arrested by the engagement of the abutment face 168 of the wiper with the shoe, the pin 172 slides through the bracket 174 to actuate the pinion 192 which operates through the connections above described to impart said swinging movement to the arm 196 and through said arm to the wiper carrying block 160. During such swinging movement, the shaft 118 moves relatively to the slide 150 through horizontal slots in the slide.

The capacity of the worm shaft 122 for endwise movement enables the operating instrumentalities to operate on either a right or a left shoe without adjustment since it permits a continued advancement of the wiper at one side of the shoe after the wiper at the opposite side of the shoe has come to the limit of its movement. In most cases the wiper at the inner or great toe side of the shoe will have a greater range of movement than the wiper at the opposite side of the shoe. Assuming that a left shoe is mounted in the machine, the right wiper, as seen in Fig. 11, would be operating on the inner side of the shoe. In the operation of the machine, the wiper at the left side of the shoe would complete its bodily advancement first and during the continued operation of the machine, the shaft 122 would move very slightly to the right to permit the right wiper to complete its bodily advancement while the left wiper remains at rest. After the bodily movement of the right wiper is arrested by the shoe, the swinging overwiping movement of the wipers is effected by the operation of the mechanism just described. Here, again, the left wiper will complete its wiping movement before the right wiper due to the difference in angle of the inside and outside lines of the shoe. Accordingly, upon completion of the overwiping movement of the left wiper, the shaft 122 will again move slightly to the right to enable the right wiper to complete its overwiping movement while the left wiper remains at rest.

The flange formers 162 are secured to the free ends of arms 206 (Fig. 11) pivoted to the upper ends of links 208 which in turn are pivoted at their lower ends to outward extensions 210 of the blocks 168. The initial elevated position of the flange formers is determined by the engagement of rolls 212 carried by the arms 206 with the bottom surfaces of plates 214 which move downwardly to operate the flange formers. It will be understood that since the flange formers 162 are carried by the blocks 168, they swing inwardly with the wipers 160, such swinging movement bringing the work-engaging portions of the flange formers into parallel relation to the insole rib. The arms 206 are yieldingly held in their elevated position illustrated in Fig. 11 by tension

springs 222 anchored at their upper ends to the outer extremities of said arms and at their lower ends to the extensions 210 of the blocks 168. The flange formers 162 are yieldingly held at the limit of their longitudinal movement away from the wipers 160 by torsion springs 224 (Fig. 14) mounted on forward extensions of pins 226 which pivotally connect the arms 206 to the links 208. The torsion springs 224 are substantially stronger than the tension springs 222 to the end that the flange formers 162 will first move downwardly upon actuation of the plates 214 by swinging movement of the arms 206 and the links 208 as a unit about the lower fulcrums of said links. After the flange formers engage the insole, further actuation of the plates 214 causes the outer extremities of the arms 206 to swing downwardly against the resistance of the torsion springs 224 and simultaneously to move outwardly by reason of the inclination of the links 208, causing the flange formers to act against the inner surface of the insole rib. For actuating the plates 214, the eccentrically operated slide 82 (Figs. 3 and 7) carries a crosshead 228 to which the lower portions of shafts 230 are anchored. These shafts extend to the upper extremity of the machine and have flanges 234 at their upper portions which flanges support the bottoms of hollow cylindrical members 232 which carry the plates 214. The shafts 230 act on the plates 214 through springs 238 surrounding the upper portions of the shafts 230 and confined between collars 240 on said shafts and the bottoms of the cylindrical members 232. It will be understood that the plates 214 apply the final flange-forming pressure equally to the wipers 160 and the flange formers 162 and consequently the wipers need not be locked in their overwiped position to receive the outward pressure of the flange formers 162.

For indenting the upper along a line defined by the apex of the angle between the overlasted portion of the upper and its upturned margin, the wipers 160 have slight flanges or beads 242 extending downwardly from their inner extremities. These beads indent the upper as the jack is moved upwardly slightly during the power cycle of the machine. This upward movement of the jack is effected by the operation of a forward eccentric 244 (Fig. 1) on the shaft 76 which eccentric operates a pitman 246 connected to a slide 248. The slide acts against a body of fluid in a reservoir 250 (Fig. 7) in the hollow upper portion of the slide. Slidably mounted within this reservoir is a hollow downward extension 252 of the table 22 which carries a valve 254 and a valve seat 256 (Fig. 7), said valve being normally held closed by a spring 258 surrounding the upper extremity of a valve stem 260. When the machine is at rest, the valve is held open by a bell crank lever 264 pivoted to the table 22 and arranged to engage the upper end of the valve stem 260. Said bell-crank lever is operated by the upward movement of the slide 82 during the latter part of the power cycle of the machine, such upward movement of the slide acting on the horizontal arm of a bell-crank lever 266 pivoted on the standard 20 and connected to the bell-crank lever 264 by a link 268. When the machine is at rest, the slide 82, being at the limit of its upward movement, holds the bell-crank levers 264 and 266 in their positions illustrated in Fig. 1 with the valve 254 in its open position. During the power cycle of the machine, the slide 82 moves downwardly permitting spring 258 to close the valve 254 and thereafter the upward movement of the slide 248 by the eccentric 244

(Fig. 1) lifts the work support and presses the shoe upwardly against the wipers 162, the hold-down 42 (Fig. 7) moving upwardly against the pressure of the spring 45 to permit upward movement of the shoe. In order to prevent excessive upward pressure of the shoe against the wipers, the slide 248 is provided with a by-pass for conducting oil from the reservoir 250 to the interior of the downward extension 252 of the table, said by-pass comprising a horizontal duct 272 from the oil reservoir 250 communicating with an upwardly extending duct 274 which is normally closed by a ball valve 276 acted on by a spring 278. The portion of the duct 274 above the valve communicates with another duct 280 through which oil from the reservoir flows into a chamber 282 extending about the downward extension 252 of the table, said chamber having a port 284 communicating with the interior of said downward extension. It will be understood that when, in the course of the upward movement of the slide 248, the resistance of the shoe to further upward movement becomes greater than the resistance of the spring 278 to the pressure of fluid against the ball valve 276, said valve will open to permit oil from the reservoir 250 to flow upwardly through the by-pass. In order to provide for the automatic opening of the ball valve 276 at the exact instant when the desired maximum upward pressure of the shoe against the wipers has been attained the spring 278 is backed up by a screw 279 (Fig. 7) which may be adjusted to provide the desired pressure of the spring against the ball valve.

For positioning the shoe lengthwise relatively to the wipers 162, the machine is provided with a backstop 286 (Fig. 7) against which the back-seam portion of the shoe abuts. The backstop is secured to the forward portion of a sliding shaft 288 splined in a bearing 290 at the back of the machine head. For adjusting the backstop 286 and for holding it in adjusted position, a bevel gear 292 is secured to an internally threaded sleeve 294 which in turn is mounted on the threaded rear portion of the shaft 288 and journaled in a bearing in a bracket 296 at the rear of the machine head and held against longitudinal movement by a collar 298 secured to the rear portion of the sleeve 294. The backstop is adjusted by turning an upwardly and forwardly extending shaft 300 having at its forward end a knurled knob 302 (Fig. 5) and at its rear end a beveled gear 304 which meshes with the gear 292.

In the operation of the machine a last 306 (Fig. 7) on which is mounted an upper 308 provided with a molded counter 310 is positioned on a heel pin 312 at the upper end of the heel post 24. Preferably, the upper 308 together with the counter 310 have been fastened to the extremity of the heel portion of an insole 314 on the last bottom and the upper has been tensioned lengthwise and temporarily tacked to the toe end of the last in the usual pulling-over operation. Preferably, the illustrated machine receives the shoe immediately after the pulling-over operation and before any lasting operations have been performed. After the last is mounted on the heel pin 312, the work support is moved rearwardly in the table 22 from its position illustrated in Fig. 1 to its position illustrated in Fig. 7 bringing the heel end of the upper into contact with the backstop 286 which positions the shoe lengthwise thereof relative to the operating instrumentalities of the machine. It will be understood that

the backstop will be adjusted to position it correctly with respect to the operating instrumentalities for shoes of the size to be operated upon. Preferably, the wipers 160 and the flange formers 162 will have been adjusted by means of the handle 150 to position them apart from each other widthwise of the shoe to an extent slightly greater than the width of the heel portion of the shoe to be operated upon. After positioning the shoe lengthwise thereof against the backstop 286 the treadle 28 is depressed to move the last upwardly until it is located heightwise thereof by the engagement of the insole 314 (Fig. 7) with the hold-down 42. As the treadle is further depressed, the wipers 160 and the flange formers 162 are moved as a unit widthwise of the shoe from their position illustrated in Fig. 11 to their position in Fig. 15. In this position the fingers 164 at the rearward extremities of the wipers 160 have overwiped the lasting margins of the upper materials including the flange of the counter at points adjacent to the ends of the insole rib 316. Continued depression of the treadle causes the wipers together with the flange formers to swing inwardly into their position illustrated in Fig. 16. As the shoe resists further advancement of the wipers the fulcrum of the treadle 28 shifts from 39 (Fig. 1) at the rearward extremity of the treadle to 52 at the central portion of the treadle and further depression of the treadle lifts the slide 54 to operate the one-revolution clutch mechanism and start the power cycle of the machine. During the first stage of the power cycle, the plates 214 (Fig. 18) move downwardly from their position in Fig. 18 to their position in Fig. 19 to bring the flange formers 162 into engagement with the insole 314 and as said plates continue their downward movement, the links 208 swing downwardly and outwardly about their lower fulcrums bringing the flange formers into contact with the opposite end portions of the rib 316 of the insole. During the downward and outward movement of the flange formers, the wipers 160 are further advanced and at the same time the work support is moved upwardly by the operation of the eccentric 244 (Fig. 1) forcing the overwiped margin of the upper materials upwardly against the bead 242 on each wiper, thus indenting the overwiped materials at the axis on which the upper materials and the flange of the counter are upturned. During the latter part of the power cycle of the machine, the flange formers move outwardly to press the insole rib 316 together with the upturned portions of the upper materials against the wipers 160 which at this stage of the operation of the machine have completed their overwiping movement and serve as abutments against which the flange formers act (Figs. 17 and 20). It will be seen from Fig. 21 that the work-engaging edge face of the wiper and that portion of the flange former which engages the inner surface of the insole rib are inclined outwardly of the shoe so as to overmold the insole rib and the upturned flange of the upper materials. The increment of overmolding thus produced is substantially commensurate with the normal spring back of the upturned portion of the counter flange after the pressure of the flange former is released.

No provision is made in the illustrated machine for fastening the upper materials to the insole rib since such fastening is performed in the subsequent side lasting and heel end lasting operation. The shape imparted to the counter by the operating instrumentalities of the illustrated ma-

chine will be maintained without the aid of fastenings by reason of the inherent stiffness of the counter material and the upper will retain the shape imparted to it to an extent sufficient to facilitate appreciably the subsequent lasting operation.

It will be understood that it is not necessary to change either wipers or flange formers for shoes of different sizes or styles since the organization of the illustrated machine is such that the wipers and flange formers automatically adjust themselves to shoes of all sizes and contours. It will also be understood that it is not necessary to adjust the operating instrumentalities to enable the machine to operate on right shoes, for example, after having previously operated on left shoes, since the automatic endwise adjustment of the worm shaft 122 (Fig. 11) enables each wiper and flange former unit to advance until it is located by the engagement of the abutment face 166 of the wiper with the shoe. Furthermore, the flange formers 162, by reason of their thin work-engaging portions, will operate equally satisfactorily on the narrowest women's shoes and the widest men's shoes. In short, the machine will operate satisfactorily on any size and style of shoe after merely adjusting the wipers and flange formers according to the width of the shoe to be operated upon.

While the machine is herein illustrated in its operation upon shoe uppers provided with counters, it is to be understood that the invention is not thus limited in its scope since the illustrated machine may be used in the manufacture of counters to prepare them for use in Goodyear welt shoes, or it may be used to shape back parts provided with counters. Such counters or back parts could be shaped over lasts in the same manner as the shoe upper herein illustrated, but, more probably, they would be shaped over a heel form which would be secured to the heel post and be a part of the machine.

Having thus described my invention, what I claim as new and desire to secure by Letters Patent of the United States is:

1. A machine for forming shoe bottom substance into upstanding flanges at opposite sides of a shoe bottom comprising oppositely disposed abutment members constructed and arranged to operate concomitantly on the outer surface of the shoe bottom substance at opposite sides of the shoe, means constructed and arranged to engage opposite sides of the shoe to determine the operative position of each abutment member widthwise of the shoe, and oppositely disposed flange formers operable to shape the shoe bottom substance against said abutment members by movement away from each other.

2. A machine for forming shoe bottom substance into upstanding flanges at opposite sides of a shoe bottom comprising oppositely disposed abutment members constructed and arranged to operate concomitantly on the outer surface of the shoe bottom substance at opposite sides of the shoe, means constructed and arranged to engage opposite sides of the shoe to determine the position of each abutment member widthwise of the shoe, oppositely disposed flange formers movable heightwise of the shoe for engagement with the shoe bottom and movable away from each other to shape the shoe bottom substance against said abutment members, and means for moving said flange formers away from each other to shape the shoe bottom substance.

3. A machine for forming shoe bottom sub-

stance into a fastening-receiving flange comprising outer flange formers, inner flange formers, means for simultaneously moving said flange formers inwardly toward each other, means for locating the outer flange formers relatively to the edge of the last bottom, and means for operating the inner flange formers to shape said shoe bottom substance against the outer flange formers.

4. A machine for shaping shoe bottom substance into fastening-receiving flanges comprising an outer flange former, an inner flange former, means for moving said flange formers as a unit toward the longitudinal median line of a shoe in the machine, means on the outer flange former for terminating such movement, and means for moving said inner flange former toward the outer flange former while the outer flange former remains stationary.

5. A machine for shaping shoe bottom substance into a fastening-receiving flange comprising outer flange formers movable to overwise the everlasting marginal materials of a shoe in the machine, and inner flange formers each having three distinct motions: first, inwardly over said marginal materials from remote positions widthwise of the shoe in paths spaced heightwise of the shoe from the shoe bottom into positions spaced inwardly of the shoe from said shoe bottom substance; second, heightwise of the shoe into engagement with the shoe bottom, and third, widthwise of the shoe to shape said shoe bottom substance against the outer flange former.

6. A machine for shaping shoe bottom substance into a fastening-receiving flange comprising outer flange formers movable to overwise the everlasting marginal materials of a shoe in the machine, inner flange formers movable from remote positions widthwise of the shoe in paths spaced heightwise of the shoe from the shoe bottom into positions spaced inwardly of the shoe from said shoe bottom substance, and means for moving the inner flange formers first heightwise of the shoe into engagement with the shoe bottom, then widthwise of the shoe toward the outer flange formers while maintaining their engagement with the shoe bottom.

7. A machine for shaping shoe bottom substance at opposite side portions of a shoe into fastening-receiving flanges comprising outer flange formers, inner flange formers, and means for operating said inner flange formers to shape said shoe bottom substance against the outer formers, said means being constructed and arranged to move said inner formers simultaneously until one of them is arrested by engagement with the shoe bottom substance and thereafter to move the other inner former independently until it, too, is arrested by engagement with said shoe bottom substance.

8. A machine for shaping shoe bottom substance at opposite sides of a shoe into fastening-receiving flanges comprising outer flange formers, inner flange formers, and means for operating said formers constructed and arranged to advance them until one outer former and one inner former are arrested by the work and thereafter to move the other outer former and the other inner former independently until they, too, are arrested by the work.

9. In a machine for forming inseam substance into an upstanding flange, an outer flange former, means for moving said flange former bodily widthwise of the shoe into engagement with the inseam substance of a shoe in the machine, and means operating thereafter to swing said former

about an axis extending generally heightwise of the shoe into a position of alinement with said inseam substance.

10. In a machine for forming inseam substance into an upstanding fastening-receiving flange, an outer flange former, means for advancing said flange former bodily widthwise of the shoe into engagement with the inseam substance of a shoe in the machine, and means rendered operative by the resistance of the shoe to further bodily movement of said flange former for swinging it into parallel relation to said inseam substance.

11. In a machine for forming an inseam substance into an upstanding fastening-receiving flange, an outer flange former, means for advancing said flange former bodily widthwise of the shoe into engagement with the inseam substance of a shoe in the machine, and means rendered operative by the resistance of the shoe to further bodily movement of said flange former for swinging it about its initial point of contact with said inseam substance into alinement with said substance.

12. In a machine for forming inseam substance into an upstanding flange, an outer flange former, a carrier therefor mounted for movement widthwise of a shoe in the machine, and a flange former holder mounted on the carrier for arcuate movement about an axis coincident with the heelward end of the work-engaging surface of said flange former, means for advancing the slide to bring the heelward end of the flange former into engagement with the inseam substance, and means for imparting arcuate movement to said holder to bring the remaining portion of said flange former into engagement with the inseam substance.

13. In a machine for forming inseam substance into an upstanding flange, an outer flange former, a carrier therefor mounted for movement widthwise of a shoe in the machine, and a flange former holder mounted on the carrier for arcuate movement about an axis coincident with the heelward end of the work-engaging surface of said flange former, means for advancing said slide to bring the heelward end of said flange former into engagement with said inseam substance, and means rendered operative by resistance of the shoe to further bodily movement of the flange former for imparting arcuate movement to said holder thereby to bring the toeward portion of the flange former into engagement with said inseam substance.

14. In a machine for shaping uppers over lasts, a pair of wipers operable to wipe the lasting margin of an upper over an insole on a last bottom by an initial movement bodily widthwise only of the last and by a subsequent swinging movement about an axis extending generally heightwise of the upper after their initial movement is completed.

15. In a machine for shaping a shoe upper over a ribbed insole on a last bottom, a pair of wipers, and means for effecting an initial movement of said wipers widthwise only of the last to overwipe sections of the heel portion of the upper adjacent to the ends of the insole rib, and for effecting a movement of said wipers subsequent to said initial movement to overwipe adjacent sections of the upper against the insole rib.

16. In a machine for shaping heel stiffeners over forms, a pair of wipers for bending the forward portions of the counter wings into parallel relation to the sole face of a form, and means constructed and arranged to act on margins of

the counter wings extending inwardly beyond said wipers to bend them about the wiping edges of said wipers into upstanding relation to the sole face of the form while the wipers hold the adjacent portions of the counter in parallel relation to said face.

17. In a machine for shaping heel stiffeners over forms, a pair of wipers for bending the forward portions of the counter wings into parallel relation to the sole face of a form and a pair of counter formers constructed and arranged to act on the margins of the counter wings extending beyond said wipers to bend them upwardly about the wiping edges of said wipers into generally rectangular relation to adjacent portions of the counter while said portions are held in parallel relation to the sole face of the form by said wipers.

18. In a machine for shaping counters over forms, a pair of wipers constructed and arranged to bend the forward extremities of the counters into parallel relation to the sole face of a form, and a pair of counter formers constructed and arranged to act on portions of the counter extending inwardly beyond said wipers to bend them into generally rectangular relation to the adjacent portions of the counter, said wipers being constructed and arranged to serve as abutments against which said counter formers bend the margin of the counter.

19. In a machine for shaping counters over forms, a pair of wipers for bending the forward portions of a counter into parallel relation to the sole face of a form, a pair of counter formers constructed and arranged to act against portions of the counters extending inwardly beyond said wipers to bend them into generally rectangular relation to adjacent portions of the counters, and means for imparting heightwise movement to the form to cause said wipers to form a crease at the bend line of the counters.

20. In a machine for shaping counters over forms, a pair of wipers for bending the forward portions of a counter into parallel relation to the sole face of a form, a pair of counter formers constructed and arranged to act against portions of the counters extending inwardly beyond said wipers to bend them into generally rectangular relation to adjacent portions of the counters, and means for imparting heightwise movement to the last to cause said wipers to form a crease at the bend line of the counters, said wipers having beads at the extremities of their wiping surfaces to promote said creasing operation.

21. In a machine for shaping uppers over lasts, a pair of wipers operable to wipe the lasting margin of an upper over an insole on a last bottom, a pair of carriers for the wipers, a pair of slides for the carriers, means for operating the slides widthwise only of the last to impart an initial movement to the wipers, and means for operating the carriers to impart an additional movement to the wipers.

22. In a machine for shaping uppers over lasts, a pair of wipers operable to wipe the lasting margin of an upper over an insole on a last bottom, a carrier for each wiper, a slide for each carrier, means for operating the slides to impart an initial movement to the wipers widthwise only of the last, and means for moving the carriers relatively to the slides to impart an additional axial movement to the wipers.

23. In a machine for shaping uppers over lasts, a pair of wipers for wiping the lasting margin of an upper in over an insole on a last bottom said

wipers being movable in rectilinear paths extending widthwise of the last to overwipe a narrow area of the heel seat portion of the upper and movable axially to overwipe portions of the lasting margin extending toewardly from said area.

24. In a machine for shaping uppers over lasts, a pair of wipers for wiping the lasting margin of an upper in over the feather of a ribbed insole and forming the upper against said rib, means for moving said wipers in rectilinear paths to overwipe an area of the heel seat portion of the upper adjacent to the end of the insole rib and extending rearwardly and inwardly beyond said rib, and means for moving said wipers axially to overwipe portions of the lasting margin extending toewardly from said area.

25. In a machine for shaping uppers over lasts, a pair of wipers for wiping the lasting margin of an upper in over the feather of a ribbed insole and forming the upper against said rib, each of said wipers having fingers operable by rectilinear movement of the wipers widthwise of the shoe to overwipe an area of the heel seat portion of the upper adjacent to the end of the insole rib beyond the line of said rib, and each of said wipers having an overwiping margin extending toewardly from said fingers and operable by movement of the wiper about an axis coinciding with the junction of said fingers and said overwiping margin.

26. A machine for forming shoe bottom substance into an upstanding flange comprising an outer flange former, an inner flange former, means one on of said formers for indenting the shoe bottom, and means for moving the shoe heightwise to cause said indenting means to operate.

27. A machine for forming shoe bottom substance into an upstanding flange comprising an outer flange former, an inner flange former, means on one of said formers for indenting the shoe bottom along a line adjacent to the root of said flange, and means for effecting relative movement of the shoe and said indenting means heightwise of the shoe to cause said indenting means to operate.

28. A machine for forming shoe bottom substance into an upstanding flange comprising an abutment member constructed and arranged to engage the outer portion of the shoe bottom substance, means on said abutment member for indenting the shoe bottom on a line coincidental with the root of said flange, a flange former operable to form said shoe bottom substance against said abutment member, and means for effecting relative heightwise movement of the shoe and the abutment member to operate indenting means.

29. In a shoe machine, means for imparting heightwise movement to a shoe in the machine including two members movable relatively to each other, said members being constructed and arranged to provide a fluid chamber, the fluid in which prevents relative movement of said members in one direction, and a valve outside said chamber through which said fluid may by-pass to permit such movement of said members.

30. In a machine for flanging the lasting margin of an upper against the rib of an insole, a flange former movable first from a remote position widthwise of the shoe inwardly over the insole rib, then heightwise of the shoe into engagement with the insole, and finally outwardly into flange forming engagement with the insole rib.

31. In a machine for flanging the lasting mar-

gin of an upper against an insole rib, a flange former constructed and arranged to operate against the inner surface of said rib, a carrier for the flange former, means for moving the carrier widthwise of the shoe to advance the flange former from a position remote from the shoe to a position over the central portion of the insole, and means operable thereafter to move the flange former heightwise of the shoe into engagement with the insole and then widthwise of the shoe into engagement with the insole rib.

32. A machine for forming shoe bottom substance into an upstanding flange comprising a pair of flange formers, a pair of wipers, a pair of carriers, one at each side of the shoe, for said flange formers and wipers, means for advancing said carriers toward the shoe including a worm shaft having two worms threaded in opposite directions, and worm gears constructed and arranged to mesh with said worms, said worm shaft being arranged for endwise operative movement to provide for operation of one of said worm gears while the other remains at rest.

33. In a machine for flanging the lasting margin of an upper against an insole rib, a flange former for shaping the lasting margin of an upper against the rib of an insole, a carrier for said flange former, said flange former being mounted for swinging movement relatively to the carrier heightwise of the shoe into insole-engaging position and for subsequent movement widthwise of the shoe into rib-engaging position, means for advancing the carrier to position the flange former over the insole, and means for thereafter swinging the carrier heightwise of the shoe and finally moving it widthwise of the shoe into rib-engaging position.

34. In a machine for forming shoe bottom substance into an upstanding flange, an abutment member and a flange former so constructed and arranged that their work-engaging surfaces extend upwardly with an inclination outward relatively to a shoe in the machine, the angle of inclination of said surfaces being such that the normal spring back of the shoe bottom substance after said members have operated upon it will bring it into a position substantially perpendicular to the shoe bottom.

35. In a machine for operating on shoe bottoms, operating means, a work support movable heightwise of the shoe, an actuator for imparting such heightwise movement to the work support, and connections from said actuator to the work support including a slide provided with a reservoir, a hollow member slidably mounted in said reservoir and provided with a port communicating with said reservoir, a valve for closing said port, a by-pass for conducting fluid from the reservoir into said hollow member when said valve is closed, and a valve for closing said by-pass, said by-pass valve being constructed and arranged to be opened by pressure of the fluid in said reservoir above a predetermined maximum.

36. In a shoe machine, a member for operating on a shoe bottom, a carrier on which said member is mounted for relative movement both heightwise and widthwise of the shoe, means for moving the carrier toward the shoe, and means for moving said member, relatively to the carrier, first heightwise of the shoe into engagement with the shoe bottom, and then widthwise of the shoe.

37. In a shoe machine, an operating member, a carrier on which said member is mounted for relative movements heightwise and widthwise of

the shoe, manually operated means for moving said carrier toward the shoe, and power-operated means for moving said member, relatively to the carrier, first heightwise of the shoe into engagement with the shoe bottom, and then widthwise of the shoe.

38. In a shoe machine, a member for operating on a shoe bottom, a carrier constructed and arranged for movement widthwise of the shoe, an arm pivoted to the carrier and extending upwardly with an inclination outward relatively to the shoe, said member being pivotally mounted on said arm, means for moving said carrier toward the shoe, and means operable first to swing said member heightwise of the shoe about its pivotal connection to said arm into engagement with the shoe bottom, and operable thereafter to swing said member about its point of engagement with the shoe bottom thereby swinging said arm outwardly and moving said member widthwise of the shoe.

39. A machine for forming inseam substance into upstanding flanges at opposite sides of a shoe bottom comprising inner and outer flange formers constructed and arranged to engage the inseam substance between them, and actuating

means constructed and arranged to apply equal flange-forming pressure to said inner and outer flange formers.

40. A machine for forming inseam substance into upstanding flanges at opposite sides of a shoe bottom comprising inner and outer flange formers constructed and arranged to engage the inseam substance between them, actuating means constructed and arranged to apply equal flange-forming pressure to said inner and outer flange formers, and means for determining the operative position of said flange formers relatively to the edge of the last bottom.

41. A machine for forming shoe-bottom substance into upstanding flanges at opposite sides of a shoe bottom comprising abutment members constructed and arranged to engage the outer surface of the shoe bottom substance, means for locating said abutment members relatively to the edge of the last bottom, flange formers operable to shape the shoe-bottom substance against said abutment members, and actuating means constructed and arranged to apply equal flange-forming pressures to the abutment members and the flange formers.

LESTER S. MACDONALD.
